United States Patent Office

Des. 199,166
Patented Sept. 15, 1964

199,166

ELECTRIC MASSAGER

Alfred W. Madl, Mequon, Wis., assignor to John Oster
Manufacturing Co., Milwaukee, Wis., a corporation of
Wisconsin

Filed Sept. 11, 1963, Ser. No. 76,554

Term of patent 14 years

(Cl. D83—1)

Fig 1 - 1

Fig 1 - 2

FIG - 3

FIG - 4

FIG - 5FIG - 6FIG. 1 is a front perspective view of an electric massager embodying my new design;

FIG. 2 is a front elevational view thereof;

FIG. 3 is a side elevational view thereof;

FIG. 4 is a top plan view thereof;

FIG. 5 is a rear perspective view thereof; and

FIG. 6 is a rear elevational view thereof.

The dominant features of my design reside in those portions shown in full lines.

I claim:

The ornamental design for an electric massager, as shown and described.
